UNITED STATES PATENT OFFICE.

GEORGE H. HAMMOND, OF MINNEAPOLIS, MINNESOTA.

COASTER AND BRAKE FOR BICYCLES.

SPECIFICATION forming part of Letters Patent No. 689,962, dated December 31, 1901.

Application filed August 6, 1901. Serial No. 71,019. (No model.)

To all whom it may concern:

Be it known that I, GEORGE H. HAMMOND, a citizen of the United States, residing at Minneapolis, in the county of Hennepin and 5 State of Minnesota, have invented certain new and useful Improvements in Coasters and Brakes for Bicycles; and I do hereby declare the following to be a full, clear, and exact description of the invention, such as will enable 10 others skilled in the art to which it appertains to make and use the same.

My present invention has for its object to provide an improved back-pedaling brake and coaster for bicycles; and to this end it 15 consists of the novel devices and combinations hereinafter described, and defined in the claims.

The invention is illustrated in the accompanying drawings, wherein like characters 20 indicate like parts throughout the several views.

Figure 1 is a view principally in horizontal section, showing portions of the frame of a bicycle and the hub of the rear wheel equipped 25 with one of my improved back-pedaling brakes and coasters. Fig. 2 is a side elevation of the parts shown in Fig. 1. Fig. 3 is a plan view in detail, showing the so-called "screw-sleeve" of the driving sprocket or member. 30 Fig. 4 is a plan view showing in detail the non-rotary half-clutch. Fig. 5 is a plan view with parts broken away, showing the shiftable double half-clutch or sleeve with friction-clutch cone; and Fig. 6 is a plan view showing 35 in detail the half-clutch member of the wheel-hub.

The numeral 1 indicates the rear tubes of the bicycle-frame, which are united at their rear ends in the ordinary way by prong bearing-forks 2. A non-rotary spindle 3 is anchored to the bearing-forks 2, as shown, by bearing-cones 4 and 5 and coöperating nuts 6. Bearing-cone 4 is made adjustable by screw-threaded engagement with the said spindle, 45 and the bearing-cone 5 is screwed against a shoulder afforded, as shown, by a squared portion 7 of said spindle. To further secure the cone 5 against rotation, it is provided with a projecting arm 8, the free end of which

is secured to one of the frame-tubes by a 50 clamp 9.

The wheel-hub 10 is formed with an internal tapered or conical bearing-surface 11, and at one end it is provided with an internal annular ball-bearing 12, between which and the 55 cone 5 bearing-balls 13 are mounted to run. At its other end the hub 10 is provided with an internal annular ball-bearing 14, between which and an intermediate cone, presently to be noted, bearing-balls 15 are mounted to run. 60 The annular bearing 14 is provided with a half-clutch 16.

A screw-sleeve 17 is loosely mounted on the spindle 3. This sleeve 17 is formed with the spiral groove 18 and at its outer end is provided with a bearing-cone 19, which coöperates with the bearing 14 and the balls 15, as previously indicated. Said cone 19 is formed at its outer end with an internal ball-runway 20, between which and the bearing-cone 70 4 bearing-balls 21 are mounted to run. The driving member, which in this illustration is in the form of a sprocket-wheel 22, is rigidly secured on the outwardly-projecting end of the cone portion 19 of the said sleeve 17. 75

A shiftable sleeve 23 is mounted on the sleeve 17 and is provided with a spiral key 24, which works in the spiral groove 18 of said sleeve 17. At one end the shiftable sleeve 23 is provided with a half-clutch 25, which coöperates with a half-clutch 16 of the hub 10. At its other end said sleeve 23 is provided with a half-clutch 26, which coöperates with a half-clutch 27 on the spindle 3. This clutch 27 is held against rotation, as shown, by the 85 engagement therewith of a squared section 28 of the spindle 3. The said half-clutch 27 is yieldingly pressed by a spring 29 on the spindle 3 against a stop-shoulder 30, formed on said spindle. 90

For coöperation with the conical internal frictional bearing-surface 11 of the hub 10 the sleeve 23 is provided with a frictional-clutch cone 31. This clutch-cone 31 is preferably made of wood fiber and, as shown, is secured 95 on the said sleeve 23 by screw-threaded engagement therewith.

The length of the shiftable sleeve 23 is such

that when its half-clutch 25 engages with the half-clutch 16 of the wheel-hub its half-clutch 26 will be held out of engagement with the non-rotary half-clutch 27. The converse is also true. Thus it will be seen that the sliding clutch-cone 31 is provided with what might be designated as a "double half-clutch," which adapts it to be connected with the hub half-clutch 16 in the one instance and with the non-rotary or anchored half-clutch 27 in the other instance. Its half-clutch 26 is adapted to be engaged with said non-rotary half-clutch 27, while the said clutch-cone 31 is pressed into engagement with the conical friction-bearing 11 of the wheel-hub. With the said bearing member 31 made of wood fiber it will of course wear away much more rapidly than if made of metal and as it wears away will require to be driven or moved farther toward the left. The spring 29 permits the half-clutch 27 to yield or move toward the left, so that the said clutch-cone 31 may always make proper engagement with its coöperating bearing-surface 11.

Under the forward - pedaling action the sprocket 22 will of course be driven in the direction indicated by the arrow marked on Fig. 2. This movement of the sprocket and its spirally-grooved sleeve 17 will move the shiftable sleeve 23 toward the right and cause its half-clutch 25 to engage the half-clutch 16 of the hub, and thereby positively drive the traction-wheel.

When the sprocket 22 is turned backward by a back-pedaling action, the half-clutch 25 will be disengaged from the half-clutch 16, so that the traction-wheel is permitted to run ahead, and the clutch 26 will be engaged with the non-rotary half-clutch 27, so that the sleeve 23 and its cone 31 will be held against rotation, while said cone will be pressed into engagement with the friction-surface 11 of the hub 10 under a force depending on the power which is exerted in the back-pedaling action. In coasting, the pedals, and consequently the sprocket 22, are simply held stationary, but are not turned backward, as in the brake-setting action.

It is of course evident that when the friction-clutch cone 31 becomes too badly worn it may be removed and another substituted therefor. The device above described is reliable and positive in all of its actions and has no parts which are liable to get out of order. It will be further understood that the device described is capable of many modifications within the scope of my invention. For instance, the driving member instead of being in the form of a sprocket might be in the form of a gear, as would be the case when the device is applied to the so-called "chainless" or "geared" bicycle.

What I claim, and desire to secure by Letters Patent of the United States, is as follows:

1. The combination with a wheel-hub having a half-clutch, of a non-rotary half-clutch,

a friction-clutch member engageable with the wheel-hub and provided with half-clutches adapting it to be alternately connected with said non-rotary half-clutch and with the half-clutch of said hub, and a driving member operating on said friction - clutch member to throw the same into and out of action and to connect its half-clutches with the said coöperating clutches, substantially as described. 75

2. The combination with a wheel-hub having an internal conical bearing-surface and a half-clutch, of a non - rotary half-clutch, a driving member having a sleeve loosely mounted but fixed against axial movement, a shiftable sleeve having screw-threaded engagement with the sleeve of said driver and provided with a conical friction-clutch member and with half-clutches at its ends, which half-clutches coöperate, one with said non-rotary half - clutch, and the other with the half-clutch of the hub, substantially as described. 80

3. The combination with a non-rotary spindle, of a non-rotary half-clutch mounted thereon, a driver mounted on said spindle and provided with a projecting sleeve, a wheel-hub mounted at one end on said spindle, and at the other end on the said driving member, by means of ball-bearings, said hub having an internal conical friction-surface and a half-clutch, and a shiftable conical friction-clutch member having screw-threaded engagement with the hub of said driver and provided with half-clutches engageable, one with said non-rotary half-clutch, and the other with the half-clutch of the said hub, which conical clutch member is thrown into and out of action on the internal friction-surface of said hub, respectively, by the forward and backward movements of said driver, substantially as described. 90

4. The combination with the non - rotary spindle 3 on adjustable cone-bearings 4 and anchored cone-bearings 5, of the hub 10 with bearings 12 and 14, friction-surface 11 and half-clutch 16, the driving member having the cone-bearing 19 and sleeve 17 with groove 18, the balls 13, 15 and 21 running respectively between the parts 5 12, 14 19 and 19 4, the sleeve 23 on said sleeve 17 having the key 24 engaging the groove 18 thereof, the half-clutches 25 and 26 on said sleeve 23, the clutch-cone 31 also on said sleeve 23, engageable with the friction-surface 11 of said hub 10, and the spring-pressed non-rotary half-clutch 27 coöperating with the said half-clutch 26, substantially as described. 100

5. The combination with the wheel having a half-clutch, of a non - rotary half-clutch spring-pressed and free for a limited sliding movement, a friction-clutch member engageable with the wheel - hub, by movement toward said non-rotary half - clutch and provided with half-clutches adapted to be alternately engaged with said non - rotary half-clutch and with the half-clutch of said hub, 110

and a driving member having screw-threaded engagement with said shiftable friction-clutch member, and operating to throw the same into and out of action and to connect the half-clutches thereof alternately with the said coöperating half-clutches substantially as described.

In testimony whereof I affix my signature in presence of two witnesses.

GEORGE H. HAMMOND.
